CENTRIFUGAL COMPRESSOR

Frank Whittle, Rugby, England, assignor to Power Jets (Research and Development) Limited, London, England

Application November 24, 1942, Serial No. 466,806
In Great Britain March 2, 1940

5 Claims. (Cl. 230—128)

1

In British specifications Nos. 456,976, 456,980 and 461,887, there were described or discussed centrifugal compressors having substantially annular air intakes on each side of the plane of the impeller wheel, and it is to such or similar compressors that the present invention relates (whether they have intakes on one or both sides of the plane of the compressors), more especially when they are combined with gas turbines; or to centrifugal compressors in which there may be difficulty in supporting the casing relatively to a bearing without obstructing an intake. The present invention seeks to provide constructional improvement affording the necessary steadiness and stiffness of mounting of compressor casings and diffusers having regard to the constructional problems which arise because of the double intake, or because of the location and arrangement of an intake; and also to the desirability of offering the minimum of resistance to the inflowing air. Where the compressor is directly connected to a gas turbine which drives it, as in the previously proposed reaction propulsion system, it may be required to support the turbine and impeller by bearings on each side of the impeller and the compressor casing needs to be very rigid relatively to the bearing housings, whilst at the same time it may be desirable to avoid the use of structural parts closely adjacent to the impeller eye. A further and important object of the invention is to afford adequate support of a wall or walls of a compressor casing against internal pressure, especially where the wall is of large area and is exposed to a substantial pressure difference. Lightness and ease and economy of construction are also obviously desirable. The invention seeks to afford these attributes.

According to the invention, a centrifugal compressor has its casing supported through the medium of a lattice or skeleton arrangement of webs or struts extending from the casing to a structural part axially spaced from the casing one side thereof, and surrounding the impeller shafting (or to such parts on each side of the casing), the said struts lying at greater radius from the axis of the shafting than air intakes formed between the casing and such structural part or parts. Preferably the struts are comprised in a triangulated structure and thus form lattice-like frames. The said structural parts may be those which enclose and support bearings for the impeller shafting. In a preferred construction the struts comprised in a triangulated lattice work are embodied in framework comprising the struts, arcuate flanges adapted to be attached to

the compressor casing, and arcuate flanges adapted to be attached to the structural parts; and the framework may be constructed in substantially semi-circular halves. The struts may be inclined in relation to the axis of the impeller so that the structure which they constitute or in which they are comprised, conforms substantially to the form of a frustum of a cone, their ends at greater radius being adjacent to the compressor casing and at lesser radius being adjacent to the structural part to which they attach the casing. Conveniently the framework comprising the struts and flanges may be made by castings, and further detail in relation to the construction will be made clear by the following description of an example.

Further, according to the invention, and in order to strengthen and stiffen the walls of the compressor casing against internal pressure, these walls carry externally, projecting parts preferably cylindrical webs, which extend substantially axially from the walls, and supporting webs extend from other parts of the walls to these webs or equivalent, the rim of which forms—as it were—a reinforcing hoop to which stress is transmitted from the wall, which hoop consequently acts in tension and prevents deformation of the wall under internal pressure. Again the following more detailed description of an example will further elucidate this feature of the invention.

The accompanying drawing illustrates the invention as applied to a double-intake single-stage centrifugal compressor, designed for inclusion in a constant pressure gas turbine aircraft propulsion engine.

The drawing comprises Figure 1, which is a sectional assembly view, and

Figure 2, which is an axial elevation of a half of the supporting structure on one side of the compressor casing.

The drawing shows a centrifugal double-intake compressor with an impeller 1 supported by shafting represented by a tail-shaft 2 and a quill-shaft 3. The impeller runs in a casing which has walls 4, which at a lesser radius are outwardly convergent (as at 4A) and at a greater radius (as at 4B) are parallel, forming a primary diffusing space. The inner boundaries of the walls are curved until they are axially directed, as shown at 4C, and bolted to a flange around the edge of these parts of the walls are extensions 5 which form walls of intake eyes. Integrally formed with the walls 4 are short cylindrical axial projections 6, carrying rims 6A.

Surrounding the tail shaft 2, is a structural

part 7, flanged at 7A, which encloses a bearing for the tail shaft 2, and such other components as may be required and to which may be attached such further assemblies as are required, for example an auxiliary-drive gearbox. Surrounding the quill-shaft is a second structural part 8 flanged at 8A likewise supporting and housing a bearing and other required components associated with the quill-shaft. It is to these parts 7, 8 that the compressor casing is required to be rigidly attached. The manner of attachment, constituting the basis of the invention, is as follows:

Four lattice-like castings are provided, each substantially as illustrated in Figure 2, and each constituted by a semi-circular flange 9, a semi-circular flange 10 of smaller radius, and a triangulated system of struts 11. The struts 11 are of streamline section to conform with the airflow which passes over them on its way into the eyes of the impeller. Each strut is also preferably "twisted" throughout its length, further to conform with the airflow, the direction of which may be expected to vary slightly at different axially and radially spaced stations. The four frame structures so constituted are assembled by bolts or studs attaching the flanges 9 to the flanges 6A, and the flanges 10 to the flanges 7A and 8A, and the pair of structures on each side of the compressor thus form virtually continuous lattice-like supports between the parts 7, 8 and the compressor casing.

Each end of each frame structure, i. e. the parts which butt together to form a diametral joint, is formed as shown in Figure 2, with a strut 11A which is axially directed instead of being inclined; these straight struts are faced at 11B, and the complementary struts 11A of the two mating structures may be inter-attached by bolts, and are shaped so as to be streamlined in section when mated together. In Figure 2 a strut 11 is shown with portions cut away to show their sectional shape and also to illustrate the "twist" previously referred to.

Extending radially between the projections 6 and rims 6A and the walls of the casing, are integral stiffening webs 12, which help the casing walls to resist deformation, especially against the pressure within the casing. In this resides an important feature of the invention; outward

loads on the walls of the casing, for example on the parts 4A thereof, are transmitted through the webs 12 to the rims 6A, which being virtually peripherally continuous are consequently resistant in tension, forming hoop like elements in which the stress tends to increase the radius. The structure comprised by the projecting parts 6, and their rims 6A, and the webs 12, can therefore be regarded as a form of trussing supporting the walls of the compressor.

The parts 7, 8 or the flanges 10 (as may be convenient) may partially support a system of intake guide elements represented generally at 13.

What I claim is:

1. A centrifugal compressor having its casing supported through the medium of an arrangement of struts extending from the casing to a structural part axially spaced from the casing and surrounding the impeller shafting and comprised in a triangulated structure forming lattice-like frames, the said struts lying at greater radius than air intakes formed between the casing and said structural part.

2. Compressor according to claim 1, in which the struts, comprised in triangulated lattice-work, are embodied in framework comprising the struts, arcuate flanges adapted to be attached to the compressor casing, and arcuate flanges adapted to be attached to the structural part.

3. A compressor according to claim 1, in which the arrangement of struts is attached to the compressor casing through the medium of a short cylindrical rimmed web extending axially from the compressor casing walls, and radial webs connecting said cylindrical web with said walls to stiffen and support the walls.

4. Compressor according to claim 1 in which the struts, comprised in triangulated lattice-work, are embodied in framework comprising the struts, arcuate flanges adapted to be attached to the compressor casing, and arcuate flanges adapted to be attached to the structural part, said framework comprising a casting.

5. A compressor according to claim 1, the struts being of streamline cross section and further being shaped with twist so as to conform with the direction of the air passing over them.

FRANK WHITTLE.
